UNITED STATES PATENT OFFICE.

FRANK MAROVITCH, OF NELSON, BRITISH COLUMBIA, CANADA.

ENGINE-STARTER.

1,185,519.

Specification of Letters Patent. Patented May 30, 1916.

Application filed September 24, 1915. Serial No. 52,524.

To all whom it may concern:

Be it known that I, FRANK MAROVITCH, a subject of the Emperor of Austria-Hungary, residing at Nelson, in the Province of 5 British Columbia and Dominion of Canada, have invented new and useful Improvements in Engine-Starters, of which the following is a specification.

This invention relates to starters for internal combustion engines, the object in view being to provide simple apparatus whereby compressed air delivered from the combustion chamber or chambers of an internal combustion engine may be conducted 10 to and trapped in a storage tank and retained therein until it is desired to again start the engine, whereupon by means of a suitable valve arrangement and operating means, the compressed air will be released 15 so as to again enter the combustion chamber or chambers of the engine for the purpose of actuating one or more of the pistons thereof until the engine takes up its own cycle of operation.

With the above and other objects in view, the invention consists in the novel construction, combination and arrangement of parts, as herein described, illustrated and claimed.

In the accompanying drawings:—Figure 20 1 is a sectional view of a multiple cylinder internal combustion engine showing the starting apparatus of this invention in its applied relation thereto. Fig. 2 is an enlarged side elevation of one of the valve 25 chambers. Fig. 3 is a vertical longitudinal section through the same to better show the check valve and cut-off.

A conventionally shows and designates an internal combustion engine of the multiple 30 cylinder type containing the pistons 1, 2, 3 and 4 reciprocating in the cylinders, and 5 designates the dash of an automobile.

In carrying out the present invention, I employ one or more valve casings 6 connected 45 by a pipe or tube 7 to the cylinder head so as to adapt the casing 6 to receive carbureted air compressed by the reciprocatory movements of the piston of the cylinder to which the valve casing is connected.

Within each casing 6 is mounted a check 50 valve 8 carried by the extremity of an arm 9 of a rocking valve stem 10 which is journaled in the opposite side walls of the casing 6 and is provided at one end thereof 55 projecting beyond the outside of the casing 6 with an arm 11 the end portion of which

resembles a hook terminating in a pointed bill or lip 12.

13 designates a spring acting against the arm 11 to hold the valve 8 normally closed. 60

Where more than one valve casing 6 is employed as shown in Fig. 1, the several valve casings are connected by a tubular manifold 14 from which a pipe 15 extends into a storage tank 16 which may be arranged at any convenient point in the motor vehicle. 65

Each of the connections 7 has incorporated therein a cut-off 17 and where several valves are employed in connection with several cylinders of the engine, all of the cut-offs are connected to and simultaneously operable by a common connecting rod 18 which extends rearwardly through the dash 5 where it is connected to an operating lever 75

19. Connected to the same lever 19 is a push rod 20 which is connected to the longer arms 21 of a series of valve opening levers each of which is pivotally mounted at 22 on the casing and provided at the extremity of its shorter arm with a pivotally mounted trip finger 23 normally sustained in its valve opening position by means of a spring 24. The trip finger 23 is normally held out of engagement with the bill or extremity 12 85 of the arm 11 which controls the valve 8 by means of a spring 25.

From the foregoing description, taken in connection with the accompanying drawings, the operation of the starting apparatus will 90 now be understood. Before stopping the engine, the ignition circuit is cut out so as to avoid firing any charges in the cylinder with which the valve casings 6 are in communication.

The lever 19 is then operated 95 so as to open the cut-offs 17 and at the same time unseat the valves 8. In such movement of the levers 21, however, the trip fingers 23 pass by the lips or bills 12 of the levers 11 and the valves 8 are returned to their seats by means of the springs 13.

However, the check valves will be unseated by the pressure of the air delivered from the cylinders into the valve casings 6 and this will continue until the engine stops and 100 a full and complete charge of compressed air is trapped in the storage tank 16. Upon releasing the pressure on the lever 19 the finger 23 snaps past the extremity of the arm 11 and assumes its normal and initial position.

When the operator desires to again start

the engine he again exerts a pressure against the lever 19 thereby opening the cut-offs 17 and also opening the valve 8. This permits the compressed air to return to the combustion chamber or chambers of the engine. Ordinarily, the compressed air trapped in the chamber 16 is carbureted and constitutes an explosive mixture so that after the cylinders are recharged by such mixture received 5 from the tank 16, and the cut-offs 17 are closed, a spark in the cylinder in which the piston is at the initial end of its firing stroke will ignite the mixture and produce the necessary impulse to start the engine.

15 I claim:—

The combination with a motor vehicle, of a compressed air storage tank, a valve chamber in communication with the combustion chamber of the engine and located between 10 the engine and said storage chamber, a 20

Copies of this patent may be obtained for five cents each, by addressing the "Commissioner of Patents, Washington, D. C."

spring closed check valve in said valve chamber, an arm fast on the stem of said check valve, a valve opening lever pivotally mounted on the valve chamber and carrying a spring positioned trip finger pivotally 25 mounted thereon, a cut-off between the valve chamber and the engine, and a manually controlled operating lever and connections for simultaneously opening the check valve and cut-off, the said trip finger allowing the 30 check valve to close automatically independently of and before the valve-opening lever is released.

In testimony whereof I affix my signature in presence of two witnesses.

FRANK MAROVITCH.
